L. Powers,

Hammer.

No 5,697.

Patented Aug. 1, 1848.

UNITED STATES PATENT OFFICE.

LEONARD POWERS, OF EDMESTON, NEW YORK.

CLAW-HAMMER.

Specification of Letters Patent No. 5,697, dated August 1, 1848.

To all whom it may concern:

Be it known that I, LEONARD POWERS, of 5
Edmeston, in the county of Otsego and State
of New York, have invented a new and use-
ful Improvement in the Common Hand-
Hammer; and I do hereby declare that the
following is a full, clear, and exact descrip-
tion of the construction and operation of the
same, reference being had to the annexed
10 drawings, making a part of this specifica-
tion, in which—

The figure in the drawing presents a side
view of the hammer as fixed upon the handle
ready for use.

15 The improvement herein described con-
sists of the curved brace A, connecting the
claws of the hammer with the handle for
the purpose of strengthening and supporting
this connection when the claws are used for
20 any ordinary purpose. The brace A is di-
vided in common with claws of the hammer,
the division extending down to where the
brace assumes the form of a strap, running
horizontally along upon the top of the han-
25 dle as from B to C, where it is flat and entire
and a strong rivet passes through this strap
as seen at C, having a head upon the under-
side as seen at D and is riveted on the upper

side of the strap at C. Instead of this rivet
a band may encompass both the strap and 30
the handle to perform the same office. This
brace and the claws of the hammer are
joined near the tip of the claws, leaving the
latter solid and of the usual shape as seen
in the figure, and leaving no obstruction to 35
the free use of the points of the claws, as
would be the case were those points ex-
tended and made to clasp the handle, as has
been heretofore done, while at the same time
the full advantage is obtained of a connec- 40
tion between the upper extremity of the
hammer, and the handle at the point C.

What I claim as my invention, and desire
to secure by Letters Patent, is—

The brace here described, connecting the 45
claws of the hammer with the hammer han-
dle, thus strengthening and supporting the
connection of the hammer and handle; while
at the same time the points of the claws are
left free to be used as in the ordinary ham- 50
mer, the whole being substantially arranged
as above set forth and described.

LEONARD POWERS.
